UNITED STATES PATENT OFFICE.

SIMON M. COLLINS, OF PUEBLO, COLORADO.

LEVEL.

1,105,493.

Specification of Letters Patent. Patented July 28, 1914.

Application filed June 10, 1913. Serial No. 772,820.

To all whom it may concern:

Be it known that I, SIMON M. COLLINS, a citizen of the United States, residing at Pueblo, in the county of Pueblo and State 5 of Colorado, have invented new and useful Improvements in Levels, of which the following is a specification.

This invention relates to a level which is adapted especially for use in determining 10 the exact inclination of surfaces, such as the roofs of buildings, or the like.

The primary object of the invention is to provide a level including a body having straight edges, a spirit tube mounted upon a 15 rotatable plate carried by the said body, and means associated therewith by which the angular position of the tube with respect to the body may be determined when the device is in use.

20 A further object is the provision of means associated with the rotatable plate upon which the spirit tube is mounted for use in connection with a carpenter's square, so that the level may be used in coöperation with a 25 square in marking timbers or boards for the purpose of cutting the same at an acute angle.

30 A still further object is to provide a device of this character which is simple in construction and which may be used with great accuracy in the capacities mentioned.

35 The invention consists in the features of construction, combination and arrangement of parts, hereinafter fully described and claimed, reference being had to the accompanying drawing, in which:

Figure 1 is a side elevation of the device, showing the same in use for determining the angle of inclination of a surface; Fig. 2 is 40 a transverse sectional view taken through a portion of the device; and, Fig. 3 is a side elevation of the device, showing the same in use in connection with a square for laying out an angular cut on a piece of timber. 45 Fig. 4 is a detail view of the device.

In the drawing, the numeral 1 designates the rectangular body of the level which is constructed preferably of wood in the usual manner and is provided medially in one of 50 its side faces with a circular recess 2 for the reception of a circular wear plate 3. A flat retainer ring 4 is positioned within the recess 2 against the outer face of the plate 3 and is of the same external diameter as 55 the latter. The plate 3 and the ring 4 may be constructed of any light and durable

metal such as aluminum or brass, and they are both secured to the body or stock 1 by means of the fastening screws 5. The ring 4 is provided on its inner periphery with 60 an annular flange 6 which is spaced from the outer face of the plate 3 and is adapted for engagement with the annular flange 7 formed on the outer periphery of the rotatable disk 8, which latter is mounted within the retainer ring for frictional engagement with the outer face of the wear plate. 65 A set screw 9 is adjustably mounted within alining openings provided in the ring 4 and the wear plate 3 with its enlarged head 70 adapted for engagement with the rotatable disk 8, so that the latter may be locked in any of its different adjusted positions thereby.

A spirit tube 10 of any ordinary well 75 known construction is secured to the outer face of the rotatable disk 8 intersecting the axis of the same, and the outer face of the disk is graduated so as to define quadrants with the longitudinal axis of the spirit tube 80 forming the division line between adjacent pairs of quadrants. The retainer ring is likewise divided into quadrants which are defined by the indicator marks 11 on the outer face thereof, one pair of the opposed 85 marks being disposed within a plane intersecting the longitudinal axis of the stock 1 at right angles to the plane of the retainer ring. The said indicator marks are intended to be used in indicating the angular 90 adjustment of the disk 8 with respect to the body or stock of the device for all purposes.

In using a level constructed in accordance with the invention just disclosed, the stock of the level is rested upon the surface whose 95 angle of inclination is to be determined, as shown particularly in Fig. 1, and the set screw 9 is operated manually so as to release the disk 8. The said disk is then rotated until the spirit tube is disposed so that 100 it will indicate a level position. When this has been accomplished, the angle of inclination of the supporting surface may be determined readily upon reference to the scale formed by the graduated outer faces 105 of the rotatable disk and the retainer ring, as should be readily understood. By adjusting the set screw 9 when the level is in this position, the rotatable disk may be locked, so that the device may be used in 110 truing up an inclined surface, such as concrete construction, the rafters of a roof, or

the like. It is to be understood, however, that the device may be used in the truing up of practically level surfaces, by resting the stock upon the side opposite to that in which the level device is mounted. By rotating the disk 8, the spirit tube will indicate whether the surface is level or not in a very accurate manner.

A stud 12 is formed at each end of the spirit tube on the division line between adjacent quadrants and projects outwardly therefrom to a suitable distance. The device is adapted, by the provision of these studs, for use in marking off boards, or timbers for the purpose of sawing or otherwise cutting the same. In performing this operation, the stock 1 is placed against the timber with either its top or bottom face in engagement with the adjacent surface of the same, after the disk 8 has been secured in the desired angularly adjusted position, as shown particularly in Fig. 3. Then a square or straight edge of any description is rested upon the disk 8 with one of its edges in even engagement with both of the studs 12, so that it overlies the object to be marked. Then, by running a pencil along the edge of the square or straight edge, whichever is used, an angular cut may be laid off, as should be readily understood by those skilled in the art to which this invention appertains.

From the foregoing description, taken in connection with the accompanying drawing, it should be apparent that I have provided a simply constructed level which may be employed in various capacities and which will be very accurate in use and will be a time and labor saving device. I desire to have it understood, however, that I may resort to minor changes falling within the scope of the invention that may be found necessary in practice.

Having thus described my invention, what I claim is:

A device of the class described comprising an elongated rectangular stock, a rotatable disk mounted within one face of the stock, a spirit tube attached fixedly to the said disk, means being provided by which the degree of angular adjustment of the disk with respect to the stock may be determined, means by which the disk may be locked in any of its different adjusted positions, and a pair of relatively spaced studs projecting outwardly from the outer face of the rotatable disk for engagement by a straight edge device mounted upon the disk.

In testimony whereof I affix my signature in presence of two witnesses.

SIMON M. COLLINS.
